UNITED STATES PATENT OFFICE.

WARREN M. HUNT, OF AMBOY, ILLINOIS, ASSIGNOR OF ONE-THIRD TO CHARLES W. RABBIT AND ONE-THIRD TO JOHN C. HUNT, BOTH OF AMBOY, ILLINOIS.

MUFFLER.

1,148,900.

Specification of Letters Patent. Patented Aug. 3, 1915.

Application filed July 31, 1914. Serial No. 854,341.

To all whom it may concern:

Be it known that I, WARREN M. HUNT, citizen of the United States, residing at Amboy, in the county of Lee and State of Illinois, have invented certain new and useful Improvements in Mufflers, of which the following is a specification.

This invention relates to mufflers for explosive engines and has for its object the provision of a simple and inexpensive device by the use of which the unpleasant and alarming noises due to the discharge of the exhaust of the engine into the open air will be diminished and practically eliminated.

15 A further object of the invention is to provide a device for the stated purpose in which the parts will be simple in construction and may be easily assembled in the course of manufacture or disassembled when 20 cleaning or repairing is necessary.

Other incidental objects of the invention will appear as the description of the same proceeds and the invention resides in certain novel features which will be particularly pointed out in the claims following 25 the description.

In the drawings, which illustrate a muffler embodying my improvements, Figure 1 is a longitudinal section of the complete device. Fig. 2 is a detail view of a cap and cone. Fig. 3 is an elevation of the head at the inlet end of the muffler with the parts carried by the same. Fig. 4 is an elevation of the discharge end of the 35 muffler.

In carrying out my invention, I employ a tubular casing 1 which is preferably cylindrical and may be of any desired dimensions according to the size of the engine to 40 which it is to be applied. This casing may be of any preferred material and will preferably be constructed of metal and provided with an asbestos lining, indicated at 2. The ends of the casing are closed by 45 heads 3 and 4 which may conveniently be of wood or other material faced upon both sides with metal as indicated and which are provided with central openings to receive the end of the exhaust pipe 5 from the engine and a sleeve 6, respectively. The head 50 3 is secured firmly upon the end of the exhaust pipe 5 by nuts 7, as clearly shown, and to the said head I secure a strap 8 which extends diametrically across the head and is secured thereto at its ends by

bolts or rivets 9. The central portion of this strap is arched, as shown clearly at 10 in Fig. 1, and to the ends of the same and the head, I secure a sleeve 11, the said sleeve having an internal annular flange 12 60 through which the said securing bolts or rivets are inserted and which is stepped to fit over the ends of the strap 8 without being spaced from the head through the remaining portion of its extent. The sleeve 65 11 is spaced from the inner wall of the casing, as clearly shown in Fig. 1, and extends inwardly to bear against a truncated cone which has its wider end bearing closely against the inner circumference of the casing and has its smaller end projected toward the exhaust pipe 5. A strap 14 is secured at its ends to the said cone at the smaller end thereof and this strap is arched so as to fit against the conical cap 15 which 70 has its apex projected toward the exhaust pipe 5 and bearing against the strap 10 at the center thereof and its wider end disposed concentric with but projected annularly beyond the smaller end of the truncated cone. Other cones 16 and caps 17 are provided in sufficient number to extend longitudinally through the entire casing and these caps and cones correspond in 75 every respect to the caps 15 and cones 13 80 just described. The head 4 has the sleeve 6 secured therein by nuts 18 and 19 as shown, and to the outer side of the said head, I secure a down-turned nozzle or spout 20. To the inner side of the head 4 85 I secure an arched strap 21 similar in construction to the strap 8, and a connecting rod 22 has its ends fitted in the said straps 8 and 21 and secured therein by nuts 23 and 24 adapted to be turned home against 90 95 the straps 21 and 8 respectively, as shown in Fig. 1 and as will be readily understood. Spacing sleeves 25 are fitted around the said connecting rod 22 between the successive caps and between the end cap 17 and 100 the strap 21 so that when the nuts 23 and 24 are turned home the several parts will be rigidly clamped together. It will, also, be readily understood that by turning these nuts home the heads 3 and 4 will be caused 105 to approach so that the annular flanges 26 thereon will be clamped against the adjacent ends of the casing and the heads thus firmly secured in the ends of the casing so that a rigid structure will be produced. 110

The muffler having been assembled and secured upon the exhaust pipe 5, the exhaust gases escaping from the engine will enter the muffler and will be deflected toward the sides of the same by the cap 15. As the gases cannot escape past the sleeve 11 and the cone 13 they will be turned inwardly toward the axis of the muffler and then pass under the edge of the cap between the same and the smaller end of the cone and then enter the cone through said smaller end and expand within the cone. The expanded gases will escape through the larger end of the cone but will be deflected by the inner wall of the casing so as to pass in rear of the cap 17 and then enter and pass through the cone 16. This tortuous circulation will be repeated and followed through all the successive cones and around all the successive caps and the spent gases will finally escape through the outlet sleeve 6 and the discharge spout 20.

The loud noises which ordinarily accompany the operation of an explosive engine are due to the sudden expansion of the exhaust gases upon reaching the open air and the consequent formation of a vacuum into which the surrounding air immediately rushes. By the use of my muffler the exhaust gases are prevented from expanding suddenly in the open air but are permitted a gradual expansion within a confined space so that there will be no sudden formation of a large vacuum and consequently no sudden inrush of air toward said vacuum. Tortuous circulation imparted to the exhaust gases will permit them to almost entirely free themselves of their energy before escaping to the open air through the spout 20 while at the same time each charge of exhaust gas will flow readily and quickly from the exhaust pipe so that there will be no choking of the said exhaust pipe and no perceptible back pressure upon the engine.

My device is exceedingly simple in the construction and arrangement of its parts and will be found highly efficient for the purpose for which it is designed.

Having thus described the invention what is claimed as new is:—

1. A muffler comprising a series of alined cones, and conical caps arranged alternately with the cones and carried by the smaller ends of the respectively adjacent cones, the larger end of each cone inclosing and spaced annularly from the cap carried by the succeeding cone.

2. A muffler comprising a series of alined cones open at both ends and all having their smaller ends projecting in the same direction, imperforate conical caps extending over the smaller ends of the respective cones and carried by and spaced from the same, the larger end of each cone inclosing the cap carried by the succeeding cone, and

means for securing the caps and cones in fixed relation.

3. A muffler comprising a series of alined cones all having their smaller ends projecting in the same direction, a series of conical caps disposed alternately with and corresponding in number to the cones, each cap being carried by and spaced from and extending over the smaller end of the respectively adjacent cone, and the larger end of each cone inclosing the cap carried by the succeeding cone, alined spacing sleeves between and bearing against the several caps and extending through the cones, and a connecting rod extending through said spacing sleeves and caps on the axes of the cones, sleeve and caps and provided with means for clamping the same in fixed relation.

4. A muffler comprising a series of alined open-ended cones, a series of conical caps arranged alternately with the cones and extending over the smaller ends of the respectively adjacent cones, straps secured to the caps and the smaller ends of adjacent cones and supporting the caps in spaced relation to said cones, spacing sleeves between adjacent caps, and a connecting rod inserted through the several sleeves and caps and securing the several parts together, the larger end of each cone inclosing the cap carried by the succeeding cone.

5. In a muffler, the combination of a tubular casing, a series of alternate caps and cones extending longitudinally of the casing, the larger ends of the cones being in contact with the casing throughout their circumference, and the caps being carried by the smaller ends of the respectively adjacent cones in spaced relation thereto and inclosed by and annularly spaced from the larger ends of the respectively preceding cones, heads closing the ends of the casing, a connecting rod connected internally to the heads and extending axially through the several caps, spacing sleeves upon said rod between the caps, and clamping devices on the ends of the rod.

6. In a muffler, the combination of a casing, a series of cones disposed longitudinally within the casing, a series of conical caps extending over and carried by the smaller ends of the respectively adjacent cones and spaced therefrom, the larger end of each cone inclosing the cap carried by the succeeding cone, heads closing the ends of the casing, a sleeve carried by the head at the inlet end of the casing and extending therefrom to the adjacent cone and bearing upon said cone near its outer edge, and means for securing the heads to the casing and the several caps and cones in fixed relation.

7. In a muffler, the combination of a tubular casing, head closing the ends of the casing, arched straps secured to the inner sides of the said heads and projecting in

wardly with respect to the casing, a connecting rod extending through and between said straps, a series of conical caps fitted upon said connecting rod, spacing sleeves 5 fitted upon the rods between the caps, open-ended cones having their wider ends bearing against the casing and inclosing caps and their smaller ends adjacent other caps, straps connecting said caps with the smaller 10 ends of the adjacent cones, a sleeve carried by the head at the inlet end of the casing and extending therefrom to the adjacent

cone and bearing upon said cone near the outer edge thereof, and clamping nuts on the ends of the rods bearing against the adjacent straps to secure the heads to the casing and the several caps and cones in fixed relation. 15

In testimony whereof I affix my signature in presence of two witnesses.
